Primary Examiner — Susan E Krakower*Assistant Examiner* — Michelle M Reeves(74) Attorney, Agent, or Firm — Mitchell Law PLLC; Matthew W. Mitchell(57) CLAIM

The ornamental design for a bench, as shown and described.

DESCRIPTION

FIG. 1 is a front perspective view of the bench of the present invention;

FIG. 2 is a top plan view thereof.

FIG. 3 is a front view thereof, the rear view being a mirror-image thereof; and,

FIG. 4 is a left-side view thereof, the right-side view being a mirror-image thereof.

The broken lines depict portions of the bench that form no part of the claimed design.
